UNITED STATES PATENT OFFICE.

EMILE JEAN ERNEST SOLOMIAC, OF ST.-MANDE, FRANCE.

AIR HEATER.

Application filed August 25, 1924. Serial No. 734,057.

This invention relates to an air-heater consisting in a metal tank or chest which is internally divided by means of sheet-iron plates or partitions into parallel compartments opening outside said tank, alternately, the ones at the bottom and at the top on the left hand side (Fig. 1) and the others at the top and at the bottom on the right hand side (Fig. 3). The first ones allow the passage of the gases moving upwardly and constitute the gas-compartments, while the latter ones allow the passage of the air moving downwardly and constitute the air-compartments. The heating fluid and the heated fluid are therefore travelling as a counter-current on both sides of the sheet iron plates separating the same, according to the accompanying drawing, in which the arrows in full lines indicate the direction followed by the gases, and the arrows in dotted lines, the way followed by the air.

In this drawing:

Fig. 1 is a vertical section made through a gas-compartment and on line 1—1 of Fig. 2.

Fig. 2 is a vertical section on line 2—2 of Fig. 1.

Fig. 3 is a vertical section made through an air-compartment and on line 3—3 of Fig. 2, tubes being shown as substituted for the bars.

Fig. 4 is a horizontal section on line 4—4 of Fig. 1.

Fig. 5 is a similar view on line 5—5 of Fig. 2.

Fig. 6 is a similar view on line 6—6 of Fig. 3.

In this drawing, 3 indicates the two external sheet-iron plates of the tank or chest. 4 are the internal sheet-iron plates; 5, the bordering or edge frames made of U-shaped iron or angle-iron. 6 are the bolts and tie-rods connecting and fastening the whole.

The chest or tank is located within a brick-work or sheet-iron flue.

This air-heater is more particularly characterized by the fact that the exchange of heat is effected mainly by transverse bars 7, the few sheet-iron plates 4, which are separated by large spaces, assisting very little in the heat exchanging.

The bars 7 present not only a larger heating surface than the sheet iron plates 4, but as they are arranged normally according to the flow of the hot gases and in quincunx

order said gases are constantly effectively mixed and come in contact with all the points of the bars, whilst the gases strike the sheet iron plates 4 in horizontal direction so that only the layers of gas on the two sides of the gas flow come in contact with said plates.

The heat-evolving bars 7 consist of round solid bars, as shown in Fig. 1, or of thick tubes, as shown in Fig. 3. They pass through the internal sheet-iron plates 4 which are for this purpose provided with holes of the same diameter as the bars, which are located exactly the one opposite the other and regularly arranged in quincunx order or so that the bars in one horizontal row stand opposite the intervals between the bars in the next lower and next upper horizontal row. They abut against the external plates 3 which are solid or plain.

These bars can be made of a single piece or of several parts, the breaking section being in this case always located close to the middle of the interspace between two internal sheet-iron plates 4.

The flue gases flowing through the gas-compartments 1 heat the transverse bars 7 which transmit the heat to the air which flows through the air compartments 2 in a direction opposite the direction in which the gases flow.

Conductivity is the main quality of the bars in question. Accordingly, these bars must be made of metal, and more particularly, whenever it is possible, of metals having a high heat conductive power.

It will of course be understood that these bars can be used in connection with other devices allowing the exchange of temperature between gaseous fluids.

The vertical tubes 8 are used for sweeping purposes. They are secured to the middle part of everyone of the gas compartments and are provided, at the height of every horizontal row of heat-evolving bars, on either side, with a small hole through which is sprayed the steam or compressed air stream which drives away the soot and other matters. The tubes 8 are branched upon a common pipe 9.

1 claim:

An air-heater comprising in combination parallel sheet iron plates widely spaced and forming alternating passages for flue gases open at the lower end in the bottom

end of the heater and at the upper end in one side of the heater, and passages for the air to be heated open at the lower end in the side of the heater opposite to the side on which said gas passages terminate and at the upper end in the upper end of the heater, and horizontal metal bars arranged in quin- cunx order traversing said parallel plates and heated by said gases in the gas passages to transmit the heat to the air in the air 10 passages.

In testimony whereof I affix my signature.

EMILE JEAN ERNEST SOLOMIAC.
